Patented Sept. 9, 1975

236,720

AUDIO-VISUAL PROJECTOR FOR CONVEYING INFORMATION

Mark P. Baker, P.O. Box 187, Beatty, Nev. 89003

Filed June 11, 1973, Ser. No. 368,770

Term of patent 14 years

Int. Cl. D19—07

U.S. Cl. D19—60

FIGURE I.

FIGURE 2.

FIGURE 3.

FIGURE 4.

FIGURE 5.

FIGURE 6.

FIG. 1 is a perspective view of the audio-visual projector for conveying information showing my new design. The picture shown on the projector is illustrative only;

FIG. 2 is an elevational view of one side of the projector;

FIG. 3 is a front elevational view of the projector;

FIG. 4 is an elevational view of the side opposite FIG. 2;

FIG. 5 is a back view of the projector; and

FIG. 6 is a top view thereof.

I claim:

The ornamental design of an audio-visual projector for conveying information, as shown and described.
